US00D777079S

(12) **United States Design Patent** (10) **Patent No.:** **US D777,079 S**
(45) **Date of Patent:** **** Jan. 24, 2017**

(54) **WIPER BLADE FRAME**

(71) Applicant: **Pylon Manufacturing Corp.**, Deerfield Beach, FL (US)

(72) Inventors: **Vambi Raymundo Tolentino**, Coconut Creek, FL (US); **Robert Peter Peers**, Boca Raton, FL (US)

(**) Term: **14 Years**

(21) Appl. No.: **29/504,287**

(22) Filed: **Oct. 3, 2014**

(51) LOC (10) Cl. **12-06**

(52) U.S. Cl.

USPC **D12/220**

(58) **Field of Classification Search**

USPC **D12/219-220**

CPC **B60S 1/4003; B60S 1/3801; B60S 2001/3815**

(57) **CLAIM**

We claim the ornamental design for a wiper blade frame, as shown and described.

DESCRIPTION

FIG. 1 is a perspective view of the wiper blade frame from the front and above.

FIG. 2. is a front view of the wiper blade frame.

FIG. 3 is a right-side view of the wiper blade frame.

FIG. 4 is a left-side view of the wiper blade frame.

FIG. 5 is a back view of the wiper blade frame.

FIG. 6 is a top view of the wiper blade frame.

FIG. 7 is a bottom view of the wiper blade frame; and,

FIG. 8 is a perspective view of the wiper blade frame from behind and below.

1 Claim, 2 Drawing Sheets
